UNITED STATES PATENT OFFICE.

FRANK R. ENGBERG, OF KINDRED, NORTH DAKOTA.

DESIGN FOR A TRACE-CARRIER.

SPECIFICATION forming part of Design No. 30,484, dated April 4, 1899.

Application filed March 9, 1899. Serial No. 708,445. Term of patent 7 years.

To all whom it may concern:

Be it known that I, FRANK R. ENGBERG, of Kindred, in the county of Cass and State of North Dakota, have invented and produced a new and original Design for a Trace-Carrier, of which the following is a full, clear, and exact description.

Reference is to be had to the accompanying drawings, forming a part of this specification, in which similar characters of reference indicate corresponding parts in both figures.

Figure 1 is a front view of a trace-carrier embodying my design, and Fig. 2 is a side view of the same.

The design comprises an oblong loop *a*, rounded at one end and having a neck *b* ex-

tending from the opposite end, the neck being furcated and return-bent, presenting a double hook *c c*, and having a groove *d* between and at the bases of the hook members *c c*.

The leading feature of the design consists in the elongated loop having at one end a neck which is furcated and return-bent, presenting double hooks.

I claim—

The design for a trace-carrier herein shown and described.

FRANK R. ENGBERG.
